UNITED STATES PATENT OFFICE.

GEORGE D. ROSENBERG, OF YOUNGSTOWN, OHIO, ASSIGNOR OF ONE-THIRD TO ERSKINE MAIDEN, JR., OF YOUNGSTOWN, OHIO.

DOORFRAME.

Application filed October 28, 1924. Serial No. 746,318.

My invention relates to door frames and is particularly applicable to water-cooled door frames for blast furnaces. The particular object of my invention is to provide 5 a new and improved frame of this type. In the drawings accompanying this specification and forming a part thereof I have shown, for purposes of illustration, one form which my invention may assume. In these 10 drawings:

Figure 1 is a front perspective of this illustrative embodiment of my invention,

Figure 2 is a section on the line 2—2 of Figures 1 and 3, showing also the adjacent 15 portions of a furnace with which this illustrative embodiment of my invention may be used,

Figure 3 is a section on the line 3—3 of Figure 2, while

20 Figure 4 is a section on the line 4—4 of Figure 2.

The furnace door frame herein shown comprises a pair of legs 11 united at their upper ends by a cross piece 12 and forming 25 with the cross piece 12 a frame work 13 in the general shape of an inverted U and divided by an annularly extending shoulder 14 into a portion 15 arranged to overlie the front face 16 of the furnace wall 17 and a 30 portion 18 arranged to extend within the furnace port 19 and formed to closely engage the sides 20 and top 21 of the port 19 and support and protect the furnace wall 17. The portion 15 is provided with projections 22 arranged to form faces 23 adapted 35 to guide the furnace door, the entire integral frame work 13 is divided by means of a transverse partition 24 into a plurality of annularly segmental sections 25 provided 40 with cooling water cavities 26 each independent of each other, the legs 11 are cut away at their lower inner corners 27 where they would otherwise closely approach the bank 28, and the entire extension 18 is tapered 45 upon its port wall engaging face 29 to facilitate withdrawal of the door frame from the port.

It will be understood by those skilled in the art that the furnace door frame herein shown and described thoroughly supports and protects the furnace wall adjacent the port, and is formed to prevent chilling of

the metal adjacent the frame, to facilitate removal of the frame without injury to the wall, and to provide means for maintaining 55 the flow of cooling water in one section of the door frame after another section has been injured to thus permit completion of the heat then in progress. It will be obvious to those skilled in the art that the door frame herein shown and described possesses 60 advantages other than those specifically pointed out and also that the particular embodiment of my invention herein shown and described may be variously changed and 65 modified without departing from the spirit of my invention or sacrificing the advantages thereof. It will therefore be understood that this disclosure is illustrative only and that my invention is not limited thereto. 70

I claim:

1. In an open hearth furnace, a water cooled furnace door frame comprising a portion overlying the adjacent furnace wall and a water cooled inverted U-shaped extension projecting from said portion within the furnace port, overlying the sides of said port, extending down to substantially the level of the molten metal within the furnace, and cut away at its lower inner corners. 80

2. In an open hearth furnace, a water cooled furnace door frame comprising a portion overlying the adjacent furnace wall and water cooled legs projecting from said portion within the furnace port, overlying the sides of said port, extending down to substantially the level of the molten metal within the furnace, and each cut away at its lower inner corner. 85

3. In an open hearth furnace, a water cooled furnace door frame comprising a water cooled inverted U-shaped extension projecting within the furnace port, overlying the sides of said port, extending down to substantially the level of the molten metal within the furnace, and cut away at its lower inner corners. 90

4. A furnace door frame for the furnace port of a masonry wall furnace, comprising an extension projecting within said furnace port and engaging the port surface of the furnace wall along a surface of contact at all points substantially parallel to the axis of said port, to thus directly and positively 100

support said wall at said port and against movement into said port, but tapered slightly to facilitate withdrawal of said frame from said port.

5. In an open hearth furnace, a water cooled furnace door frame comprising water cooled legs projecting within the furnace

port, overlying the sides of said port, extending down to substantially the level of the molten metal within the furnace, and ¹⁰ each cut away at its lower inner corner.

In testimony whereof, I hereunto affix my signature.

GEORGE D. ROSENBERG.
